CERTIFICATE OF CORRECTION

PATENT NO. : Des. 592,502 S
APPLICATION NO. : 29/306990
DATED : May 19, 2009
INVENTOR(S) : Stefano Casebasse

Page 1 of 1

It is certified that error appears in the above-identified patent and that said Letters Patent is hereby corrected as shown below:

Title Page

In the description, the following paragraph should be added at the beginning, before the listing of the figures:

“This design application claims priority to European Community design application No. 000813191 filed on October 22, 2007, which is incorporated herein by reference. All the material from European Community design application No. 000813191, which is essential to the claimed design, is included in this application. Any material in European Community design application No. 000813191, which is not present in this application, forms no part of the claimed design.”

Signed and Sealed this

Twenty-fifth Day of August, 2009

David J. Kappos
Director of the United States Patent and Trademark Office
